UNITED STATES PATENT OFFICE.

HARRY R. HOLDEMAN, OF LOS ANGELES, CALIFORNIA, ASSIGNOR TO THE J. N. FELDMAN CO. INC., OF LOS ANGELES, CALIFORNIA.

DESIGN FOR A GOTHIC-EFFECT LIGHTING-FIXTURE BANDING.

Application filed April 18, 1927. Serial No. 21,631. Term of patent 3½ years.

To all whom it may concern:

Be it known that I, HARRY R. HOLDEMAN, a citizen of the United States, residing at Los Angeles, in the county of Los Angeles and State of California, have invented a new, original, and ornamental Design for a Gothic-Effect Lighting-Fixture Banding, of which the following is a specification, reference being had to the accompanying drawing, forming part thereof.

The figure is a perspective view of a Gothic effect lighting fixture banding, showing my new design.

I claim:

The ornamental design for a Gothic effect lighting fixture banding as shown.

HARRY R. HOLDEMAN.
